US00D781891S

(12) **United States Design Patent** (10) Patent No.: **US D781,891 S**
(45) Date of Patent: ** *Mar. 21, 2017

(54) **DISPLAY SCREEN WITH GRAPHICAL USER INTERFACE**

(71) Applicant: **Go Daddy Operating Company, LLC**,
Scottsdale, AZ (US)

(72) Inventors: **Nitin Gupta**, Mountain View, CA (US);
Tapan Kamdar, San Jose, CA (US);
Edward J. Karcher, III, Chandler, AZ
(US); **Garrett Matsudaira**, Bellevue,
WA (US); **Stacy Steinkuller**, Phoenix,
AZ (US)

(73) Assignee: **Go Daddy Operating Company, LLC**,
Scottsdale, AZ (US)

(*) Notice: This patent is subject to a terminal disclaimer.

(**) Term: **14 Years**

(21) Appl. No.: **29/512,246**

(22) Filed: **Dec. 17, 2014**

(51) LOC (10) Cl. **14-04**

(52) U.S. Cl.

USPC **D14/486**

(58) **Field of Classification Search**

(57) **CLAIM**

The ornamental design for a display screen with graphical user interface, as shown and described.

DESCRIPTION

The patent file contains at least one drawing executed in color. Copies of the patent file with color drawing(s) will be provided by the Patent Office upon request and payment of the necessary fee.

The FIGURE is a view of a display screen with graphical user interface.

The dot-dash broken line in the FIGURE represents the display screen and forms no part of the claimed design.

1 Claim, 1 Drawing Sheet
(1 of 1 Drawing Sheet(s) Filed in Color)
